KNOCKDOWN PEDESTAL TABLE WITH
STORAGE RECEPTACLE

Leonard S. Baker, Clarksdale, Miss.

Application May 11, 1950, Serial No. 161,381

3 Claims. (Cl. 311—102)

1

This invention relates to furniture and has special reference to a table consisting of separable parts one of which constitutes a receptacle for the remainder of the parts, the device being preferably termed a knockdown table.

One important object of this invention is to provide a novel arrangement of separable parts in a table, such parts being capable of assembly in a set up arrangement wherein no bolts or screws are necessary to hold the parts assembled.

Another important object of this invention is to provide a novel arrangement for storing separable parts in one part of the table.

A further object of the invention is to provide a novel arrangement of the separated parts for storage, the arrangement being such that the stored parts of the table will not be accidentally displaced from the part wherein they are stored.

A still further object of the invention is to provide a novel storage arrangement whereby stored parts are prevented from rattling.

Another object of the invention is to provide a lightweight, portable, pedestal type table which permits the users thereof to seat or remove themselves without accidental jarring of the table, as is often the case in a light portable table having four corner legs.

A further object of the invention is to provide a knockdown pedestal type table which is light in weight but very stable and which provides for storage of the parts in the top thereof.

With the above and other objects in view, as will be presently apparent, the invention consists in general of certain novel details of construction and combinations of parts hereinafter fully described, illustrated in the accompanying drawings, and particularly claimed.

In the drawings, like characters of reference indicate like parts in the several views, and

Figure 1 is a side elevation, partly broken away and in section, of the table with its parts assembled and set up;

Figure 2 is a bottom plan view of the table with the parts disassembled and partly stored;

Figure 3 is a side elevation of the table with the parts arranged as in Figure 2; and

Figure 4 is a vertical median section showing the table with the parts completely stored.

In the embodiment of the invention as here disclosed the table is provided with a top 10. This top is here shown as rectangular in plan but may be of any desired shape. Extending downwardly from the top 10 is an apron 11 having sides which are arranged at right angles to each other so as to provide a substantially square enclosure. 55

2

When the form of the top is square in plan, the apron will preferably extend downwardly from the periphery of the top. Centrally beneath the top is fixed a boss 12 having a socket 13 formed therein to open downwardly. In order to brace the top 10 ribs 14 extend radially from the boss 12 to the junctions of the sides of the apron 11. Extending inwardly from the lower edges of the sides of the apron 11 are flanges 15 having their ends meeting at the corners of the apron. One opposite pair of the flanges 15 is partially cut away as at 16, these cut away portions confronting each other. On the inner face of each side of the apron 11 is fixed one end of a leaf spring 17, the other end of which is bowed toward the boss 12. Also, under two of the ribs 14 are fixed leaf springs 18 of inverted C-shape. The parts above described form the table top with a storage compartment on its under side.

20 The table has a single leg 19 of a shape and size to be gripped and held securely by the C springs 18. At its upper end this leg is reduced as at 20 to fit snugly in the socket 13. At its lower end the leg 19 is similarly provided with a reduced end 21.

25 The base 22 of this table is of circular formation in plan and is provided on its upper face with a low frusto-conical central portion 23 having an upwardly opening socket 24 formed therein for reception of the reduced end 21 of the leg 19. The base 22 is of less diameter than the distance between opposite sides of the apron 11 and is of slightly greater diameter than the distance between opposed edges of the flanges 15, the parts 30 16 being sufficiently cut away to allow the base 22 to pass between them.

35 In arranging the leg and base for storage they are detached from the top and separated one from the other. The leg 19 is then placed in the spring clips 18. The base, as shown in Figure 2, then tilted and pushed through the cut away spaces of the flanges 15 in the direction of the arrow A until it engages against the spring 17 on the apron side remote from the spaces 16. At this time the opposite edge of the base will be 40 in position to clear the opposite flange edge and is pushed up above the flange. It is now moved, with aid of the resilience of the spring 17 on the apron remote from spaces 16 in a direction opposite to the arrow A, compressing the spring on the side of the apron with which it will then engage. The base will thus be automatically centered and spring held against rattling by the four springs 17 and cannot be accidentally freed 45 from its stored position.

What is claimed is:

1. In a knockdown table, a top, an apron depending from said top and having sides forming the walls of a substantially square receptacle, flanges extending inwardly from said apron sides, a base resting on said flanges when housed within said receptacle, one pair of said flanges having cut away portions providing gaps through which the base is slid for housing and withdrawal, and a leg supported in said receptacle between the 10 top and base.

2. In a knockdown table, a top, an apron depending from said top and having sides forming the walls of a substantially square receptacle, flanges extending inwardly from said apron sides, a base resting on said flanges when housed within said receptacle, one pair of said flanges having cut away portions providing gaps through which the base is slid for housing and withdrawal, springs carried on the apron sides and bearing against opposite parts of the edge of said base when resting on said flanges, and a leg supported in said receptacle between the top and base. 15

3. In a knockdown table, a top, an apron depending from said top and having sides forming the walls of a substantially square receptacle, 20

flanges extending inwardly from said apron sides, a base resting on said flanges when housed within said receptacle, one pair of said flanges having cut away portions providing gaps through which the base is slid for housing and withdrawal, springs carried on the apron sides and bearing against opposite parts of the edge of said base when resting on said flanges, a leg supported in said receptacle between the top and base, and spring clips opening downwardly from said top for engaging and supporting said leg. 5
